UNITED STATES PATENT OFFICE.

SAMUEL B. LONG, OF SHELLSBURG, PENNSYLVANIA.

BRAKE-SHOE.

SPECIFICATION forming part of Letters Patent No. 259,179, dated June 6, 1882.

Application filed April 17, 1882. (No model.)

To all whom it may concern:

Be it known that I, SAMUEL B. LONG, of 5
Shellsburg, in the county of Bedford and State
of Pennsylvania, have invented certain new
and useful Improvements in Brake-Shoes for
Vehicles; and I do hereby declare that the fol-
lowing is a full, clear, and exact description
of the invention, which will enable others
skilled in the art to which it appertains to make
10 and use the same, reference being had to the
accompanying drawings, which form a part of
this specification, and in which—

Figure 1 is a perspective view of the brake-
block, with its shoe or rubber and clamp-bolts.
15 Fig. 2 is a similar view of the block with the
shoe removed, and Fig. 3 is a cross-section
through the block and shoe.

Similar letters of reference indicate corre-
sponding parts in all the figures.
20 My invention has relation to wagon-brakes;
and it consists in an improved construction of
the brake-block, to which the shoe or rubber
(which bears against the wheel in applying or
setting the brake) is attached, having for its
25 object to hold the shoe firmly at all times with-
out slipping, while at the same time it can
easily be removed, when required, for renewal.

In the accompanying drawings, A repre-
sents the brake-block, to the front side or face
30 of which is secured by bolts B B an angle-
plate, C, the face of which has a series of pro-
jecting teeth or sharp points, D D.

E E are clamp-bolts, which are inserted
transversely through the brake-block parallel
35 to each other, and nutted at their outer ends
upon the back plate, F, of the brake-block.

G is the brake-shoe or rubber, which is held
between the clamp-bolts E E, as clearly shown

in the drawings. By tightening up the nuts
of the latter the teeth or pointed projections 40
D of face-plate C are forced into the wood of
the rubber, thus holding it firmly in place and
preventing its moving either up or down, while
the clamps, in conjunction with the teeth, pre-
45 vent lateral or sidewise motion of the shoe
upon the block. To detach or readjust the
shoe, all that is necessary is to loosen the clamp-
bolts, when the shoe will readily come off with-
out hammering. The shoe may be made simply
50 from a flat piece of plank, of suitable length,
and thickness, shaped to fit between the clamps,
and does not require to be cut or shaped with
tapering sides and face, as it is not wedged
upon but clamped to the block A.

I am aware that it is not new to construct 55
detachable brake-shoes with clamps by which
they are fastened upon the brake block or
beam, or to make said block or beam with a
notched or serrated face for the better attach-
ment of the shoe; nor do I claim such construc- 60
tion, broadly; but

What I claim as my improvement, and de-
sire to secure by Letters Patent of the United
States, is—

The brake-shoe G, attached to the face-plate 65
C, having pointed projections D, and brake
block or beam A, by the clamp-bolts E E, nutted
to the back plate, F, of the brake-beam, as
shown and specified.

In testimony that I claim the foregoing as 70
my own I have hereunto affixed my signature
in presence of two witnesses.

SAMUEL B. LONG.
